UNITED STATES PATENT OFFICE.

FRED E. YOUNGS, OF ALLEGHENY, PENNSYLVANIA.

GAS-ENGINE.

SPECIFICATION forming part of Letters Patent No. 789,246, dated May 9, 1905.

Application filed March 1, 1893. Renewed July 13, 1904. Serial No. 216,356.

To all whom it may concern:

Be it known that I, FRED E. YOUNGS, of Allegheny, in the county of Allegheny and State of Pennsylvania, have invented a new and useful Improvement in Gas-Engines, of which the following is a full, clear, and exact description, reference being had to the accompanying drawings, forming part of this specification, in which—

10 Figure 1 is a front elevation of my improved gas-engine. Fig. 2 is a side elevation thereof. Fig. 2' is a detail of part of the igniting mechanism. Fig. 3 is a vertical section on the line III III of Fig. 2. Fig. 4 is a sectional view of the cylinders with the parts in the same position as in Fig. 3, but shown on a larger scale. Fig. 5 is a horizontal section on the line V V of Fig. 4. Fig. 6 is a vertical section on the line VI VI of Fig. 3, showing the valve and valve-chamber; Fig. 7, a vertical section taken through the cylinder 2 on the line VII VII of Fig. 3. Fig. 8 is a horizontal section on the line VIII VIII of Fig. 4, showing the exhaust-ports and the igniters. Fig. 9 is a longitudinal sectional view of one of the igniters, showing it on a scale larger than that of the other figures.

Like symbols of reference indicate like parts in each.

30 The object of my invention is to provide a gas-engine of improved power and efficiency capable of giving one explosive impulse per cylinder at each revolution. This result is in every way desirable, since as compared with other engines in which more than one revolution intervenes between successive explosions in each cylinder there is a great loss of power and efficiency, and many of the gas-engines heretofore devised for the purpose of saving that loss have had many inherent defects, which I remedy. I effect the desired result by providing the engine with at least two power-cylinders, so constructed and arranged as to serve not only as power-cylinders, but 45 to act reciprocally as feeding-cylinders, each in turn receiving and compressing an explosive charge and delivering it to the other. Designating these power-cylinders as Nos. 2 and 3, the engine is capable of performing at 50 each revolution the following cycle of opera-

tion: first, explosion and outstroke of piston in 3 and instroke in 2, effecting in the outer end of 3 compression of explosive charge previously received therein and its subsequent displacement into the inner end of 2 and effecting in 2 the displacement of previously exploded gas through the exhaust and the in-draft into the outer end of explosive fluid for cylinder 3 and next the final compression, at the inner end, of the explosive fluid received from 3; second, explosion and outstroke in 2 and instroke in 3, effecting reciprocally the operation described above—viz., in 2 compression of explosive charge previously received therein and its eventual displacement into the inner end of 3 and effecting in 3 the displacement of previously exploded gas from the inner end through the exhaust and the in-draft into its outer end of the explosive fluid for 2, and next the final compression, at the inner end, of the charge of explosive fluid received from 2.

The foregoing is a limited statement of the cycle of the engine, which will serve to explain its principle. A broader statement thereof is contained in the claims, since modifications may be made therein by utilizing parts of my invention, and thus *pro tanto* deriving its advantages.

In the drawings, 2 3 represent the power-cylinders of the engine. 9 10 are the pistons, connected with the same crank-shaft 11 and set so that they shall act reciprocally and alternately with reference to each other. Each cylinder is provided with an exhaust-port 4 4', controlled by an exhaust-valve 5, the operating mechanism of which I shall describe below. Each cylinder has also at its inner end an inlet-port 6 6' for the introduction of the explosive charge and at its lower end a port 7 7', communicating with a passage 8, through which explosive gas or a mixture of explosive gas and air is introduced from a suitable source of supply.

12 12' are ports leading to a chamber containing the igniter, which may be of any suitable construction, either an electrical igniter, a tube-igniter, &c. The ports 12 12' and the ports 6 6' and 7 7' open into a valve-chamber 13, containing a piston-valve 14, which is com-

mon to both cylinders and is reciprocated within the valve-chamber by means of a rod 15 and cam 16. Said valve has a hollow stem, as shown, and at each end thereof a head with lateral ports 17 17', adapted to register when in different positions simultaneously with the ports 6 7' or with the ports 7 6' and to connect the same with each other by way of the passage in the hollow valve-stem. At the upper end the valve has also surface ports or passages 18 18', adapted at different positions of the valve, respectively, to connect the inlet-port 6 with the igniter-port 12 and the inlet-port 6' with the igniter-port 12'. At the outer end of the valve is a port 19, which extends by a passage 19' through the valve-head to the explosive-inlet chamber 8. This port is adapted to register with the ports 7 7', respectively, at different positions of the valve's stroke and to connect the same with said chamber 8.

In Fig. 3 I show the engine with the parts in the position which they occupy when the piston 9 has completed its outstroke and the piston 10 has completed its instroke. At these positions the valve has moved so as to connect the inlet-port 6' of the cylinder 3 with its igniter-port 12', and the explosive charge in the cylinder 3, communicating with the igniter through said ports, is exploded and immediately propels the piston 10 outward, the piston 9 simultaneously moving inward. Very shortly after the explosion the valve 14 moves downwardly so as to connect the port 7 of the cylinder 2 with the port 19 and passage 19' of the valve, and through said passage brings the portion of said cylinder on the outer side of the piston into communication with the explosive-supply 8; but the port 17' is then not yet in communication with the port 7' of the cylinder 3. Now as the piston 9 proceeds in its instroke the suction generated by its inward motion will draw into the outer end of the cylinder 2 a quantity of explosive gas from the supply 8, and at the inner end of the cylinder 2 (the exhaust-valve 5 having been opened) the outstroke of the piston 9 expels the previously-expelled charge. Simultaneously with the intake of the explosive charge into the outer end of the cylinder 2 the outstroke of the piston 10 compresses within the outer end of its cylinder the charge of explosive mixture, (which had previously been drawn into its outer end from the supply 8.) The cam which actuates the main valve 14 is so timed that when the piston has progressed sufficiently to raise the pressure of the explosive mixture at the outer end of the cylinder 3 to the desired degree (say about sixty pounds) the valve shifts and brings the ports 7 17' and the ports 6 and 17, respectively, into register, whereupon the compressed explosive mixture is displaced through the ports 7 17', hollow valve-stem, and ports 17 8 into the inner end of the cylinder 2, where it is further compressed by the com-

pletion of the instroke of the piston 9. Immediately after the beginning of the inflow of the charge into the cylinder 2 the exhaust-valve of that cylinder is closed. When the piston 9 has reached the limit of its instroke and the piston 10 the limit of its outstroke, the valve 14 is shifted by its cam mechanism so as to bring the passage 18 into communication with the inlet-port 6 and with the igniter-port 12, thereby causing the ignition and explosion of the charge in the cylinder 2, the outstroke of the piston 9, and the simultaneous instroke of the piston 10. During the first period of the outstroke of the piston 9 it compresses at the outer end of the cylinder the explosive charge which was drawn thereinto on the instroke, (the port 7 having been closed by the shifting of the valve when the ports 6 and 7' were connected,) and when the piston has reached the predetermined point at which the mixture is properly compressed the valve is shifted by its cam so as to connect the ports 7 and 6' by way of the hollow valve-stem in like manner as before explained and to cause the displacement of the compressed gaseous mixture into the inner end of the cylinder 3. During the first part of the instroke of the piston 10 the valve brings the port 19 into register with the port 7', and thereupon the piston sucks an explosive charge into the outer end of the cylinder 3 through the said ports 19 and 7', while from the inner end of the cylinder the previously-explored gas is displaced through the exhaust-passage 4 and the then open exhaust-valve. During the latter part of the instroke of the piston 10 it compresses in the inner end of its cylinder the charge then being received from the outer end of the cylinder 2, the valve having been shifted, as before explained, to put the ports 7 and 6' into communication. At the end of the instroke the valve is shifted so as to put the igniter-port 12' by way of the passage 18' into communication with the port 6', whereupon the explosion takes place and the cycles of operation above explained are repeated. The ports 8 and 6' extend around or nearly around the entire periphery of the valve-chamber 13, so that when the passages 18 or 18' of the valve is brought opposite thereto and the explosion occurs the impetus of the explosion is exerted upon nearly all parts around the periphery of the valve at the plane opposite the port of the cylinder wherein the explosion occurs. The valve is thus balanced and the explosion does not cause any excessive pressure against one side of the valve-chamber or consequent undue wear of the valve at any point. The same result may be attained in substantially the same way by extending the passages 18 and 18' around or nearly around the head of the valve.

The mechanism which I prefer to use in operating the exhaust-valves is shown in Figs.

1 and 2. Each valve has a projecting stem 20 20' and a spring 21 21', which normally keeps the valve seated. A rock-lever 22 has its arms set opposite to the valve-stems and is 5 oscillated by means of a cam 23 on the engine-shaft, connected therewith by suitable rod-and-lever mechanism 24, the cam being timed so as to rock the lever and to open and close the valves at the proper point in the 10 cycle of the engine, as above explained.

The cam for operating the engine-valve is arranged in a new and improved manner. Said cam 16 has a radial slot by which it is fitted on one of the cranks 25 of the engine-shaft. The slot is made somewhat wider than the crank, so as to permit the cam to be adjusted laterally thereon, and the cam is held in such adjustment by set-screws 26. The 15 setting of the cam on the crank affords a very 20 strong and compact construction.

The igniter mechanism which I prefer to use in connection with the engine is shown clearly in Figs. 1, 8, and 9. I prefer to use it in connection with the igniter-valve mechanism above described, which brings the igniter-port into communication with the cylinder at the proper instant before its closing. The igniter mechanism consists in an electrical igniter the terminals of which are provided 25 with mechanism for making or breaking contact in order to cause the igniting spark and which are also adapted to be moved when in contact with each other by motion other than that of the make and break of contact, so as by abrasion to keep the contact 30 surfaces clean and to prevent the accumulation of a film of oxid, which by insulation impairs the efficiency of the device by rendering its sparking uncertain. The igniter mechanism 35 also consists in certain other features of construction, among which is an electrical igniter having contact-terminals, one of which is concave and the other of which is adapted to fit within it. This construction causes the 40 terminals to center in their contact, to wear evenly when rotated, and to maintain their proper shape. This constitutes an item of 45 great practical importance in the operation of the engine. In the drawings, 27 represents the 50 fixed igniter-terminal, and 28 is the other terminal, which is set in its case so as to be movable to and from the end of the terminal 27. It has a spring 29, which normally keeps its 55 end in contact with the end of the terminal 27, and the terminals project into the igniter-chamber 30, as shown in Fig. 8. They are 60 preferably set in a movable box or casting 31, which can be taken as a whole from and set into a cavity in the frame of the engine, as 65 shown in Fig. 6. 32 represents the wires leading from the igniter-terminals to the dynamo or other suitable source of electricity. Each cylinder of the gas-engine is provided with its own igniting mechanism, 70 and in each the terminal 28 is adapted to be

moved back at stated times from contact with the other by means of a rock-shaft 33, having projecting arms 34, each of which fits around and is adapted to move a stem of the igniter-terminal 28 of one of the igniting devices. 75 The lever 34 is not connected positively with the igniter-stem, but is forked and fits loosely around the same in order to have some loose motion. Consequently said lever will move freely to some extent without moving the igniter-stem; but near the end of its stroke it engages a head 34' on said stem, striking it with a sudden blow, and thus breaking the contact suddenly. This construction is desirable, because by it I am enabled to effect 80 the spark at the precise instant when it is desired. The shaft 33 is rocked by a rod 35, extending from a crank on the rock-shaft to the rock-lever 22 of the exhaust mechanism or other suitable moving part of the engine, 85 controlled, by cam or otherwise, so as to effect the separation of the terminals at the proper instant to produce explosion. Independently of this motion required to separate the terminal 28 from the other it has another motion, preferably a rotating motion on its longitudinal axis, which may be conveniently effected by a small crank 37, Fig. 9. The meeting ends of the terminals are preferably 90 respectively concave and convex, and if occasionally while they are in contact the terminal 28 be rotated the friction of the meeting surfaces will cause an abrasion, which will keep the surfaces clean and will render the 95 sparking action certain. The separation of the terminals need not be accomplished by a longitudinal motion, since the same principle of construction may be modified and applied to igniters having terminals differently operated. Instead of rotating the terminal rod 100 28 by hand it may be connected by suitable connecting devices to one of the moving parts of the engine, and thus rotated mechanically either continuously or intermittently. In order to exclude dirt, I prefer to cover the outer 105 end of the igniter-stem by a removable cap 39, which fits over a chamber 38, into which the stem projects.

The cylinders of the engine are provided with suitable water-jacket spaces, through 115 which is maintained a circulation of water in order to prevent overheating of the parts. As I do not claim herein the arrangement of such water-spaces, I shall not particularly describe the same, although they are shown in 120 the drawings. The engine may also be provided with other usual appliances—such as governing mechanism of any suitable type, &c.—which I need not particularly describe.

The advantages of my invention will be appreciated by those skilled in the art.

Within the scope of my invention as defined in the claims many modifications in the form, construction, and relative arrangement of the parts may be made. Each claim de- 130

fines an item of invention unlimited by qualifications expressed in other claims.

I claim—

1. A gas-engine having two power-cylinders, each of which communicates at its outer end with an inlet for fluid to be used in effecting explosion and with the inner (explosion) end of the other cylinder, each of said cylinders being adapted thereby to receive a charge of such fluid and to compress and deliver it to the other cylinder, a valve controlling the ports at the inner and outer ends of the cylinder and having a passage through it for passage of explosive mixture, said valve being so timed in its motion as to connect the outer end of one cylinder with the inner end of the other, after the explosive charge has been compressed in the first-named cylinder, and to open the port at the inner end of the one cylinder at substantially the same time with the opening of the port at the outer end of the other cylinder; substantially as described.
2. A gas-engine having two power-cylinders, each of which communicates at its outer end with an inlet for fluid to be used in effecting explosion, and with the inner (explosion) end of the other cylinder, each of said cylinders being adapted thereby to receive a charge of such fluid and to compress and deliver it to the other cylinder, and a piston-valve having a hollow stem affording connection between said cylinders by way of said hollow stem, said valve being a single-valve mechanism with heads and ports at each end; substantially as described.
3. A gas-engine having two power-cylinders, 2 and 3, and a hollow valve affording a connection between the inner and outer ends

of said cylinders respectively, and affording also a connection with an igniter-port, said valve being so timed in its motion relatively to the motion of said pistons that the following cycle shall be effected at each revolution: first, explosion and outstroke of piston in 3, and instroke in 2, effecting in the outer end 45 of 3 compression of explosive charge previously received therein, and its subsequent displacement into the inner end of 2, and effecting in 2 the displacement of previously exploded gas through the exhaust and the in-draft into the outer end of explosive fluid for cylinder 3, and next the final compression, at the inner end, of the explosive fluid received from 3; second, explosion and outstroke in 2, and instroke in 3, effecting reciprocally the 55 operations described above, viz: in 2 compression of explosive charge previously received therein, and its subsequent displacement into the inner end of 3, and effecting in 3 the displacement of previously-exploded gas 60 from the inner end through the exhaust, and the in-draft into its outer end of the explosive fluid for 2, and next the final compression at the inner end of the charge of explosive fluid received from 2, the charge being admitted 65 into the inner end of the one cylinder at substantially the same time with its displacement from the outer end of the other; substantially as described.

In testimony whereof I have hereunto set 70
my hand.

FRED E. YOUNGS.
